C. A. TRAHN

ELEVATOR LOCK

Filed March 5, 1923

INVENTOR:

CHARLES A. TRAHN,

By: Otto H. Rininger,
his Atty.

UNITED STATES PATENT OFFICE.

CHARLES A. TRAHN, OF LOS ANGELES, CALIFORNIA.

ELEVATOR LOCK.

Application filed March 5, 1923. Serial No. 622,921.

To all whom it may concern:

Be it known that I, CHARLES A. TRAHN, a citizen of the United States, residing at Los Angeles, in the county of Los Angeles and State of California, have invented a new and useful Elevator Lock, of which the following is a specification.

This invention relates to devices for preventing the operation of an elevator unless all doors are securely closed.

One of the objects of this invention is to provide a device that is so designed that it will securely lock before the operating circuit can be closed.

Another object is to provide a device that will mechanically close the operating circuit and make contact by the locking movement of the device.

Another object is to provide a device that will mechanically open the operating circuit and break contact by the unlocking movement of the device.

Another object is to provide a device that will not unlock before the operating circuit is opened.

Another object is to provide a device in which the locking mechanism is so arranged that the contacts are moved in a shifting direction as well as for the making and breaking of the contacts so as to promote a cleaning of the contact surfaces through the opening and closing of the contacts.

Other objects will appear from the following description and appended claims as well as from the accompanying drawing, in which—

Fig. 1 is a fragmentary rear-side elevation of elevator gates or doors, of the bi-parting type, having the locking and safety mechanism indicated in proper position.

Fig. 2 is a fragmentary rear-side elevation of an elevator door of the sidewise sliding type, having appropriate locking and safety mechanism indicated in proper position.

Fig. 3 is a front elevation of a contact-lock, having the cover-plate removed.

Fig. 4 is an end elevation of the lock in Fig. 3, as seen in the direction of the arrow 4, a cover-plate being illustrated in this view in proper relation to the lock.

Fig. 5 is a fragmentary sectional view of the lock-casing, taken on approximately the line 5—5 of Fig. 4, though slightly modified,

having no lugs on the top, and having only 55 a slot in the end for the locking latch to pass into the casing.

Fig. 6 is a top plan view of the contact plate.

Relying on springs and other automatically operating mechanism for opening or closing the operating circuit of elevators, cannot be said to assure safety in the operation of elevators.

A spring is liable to become weaker or even break, thereby making a safe operation of a contact-switch very questionable.

Even certain counter-weights, retaining the original, certain and positive operating capacity, may fail to work or operate a 70 sticky switch.

A contact-switch may easily become sticky or hard to be operated through many and different causes. Dust, badly applied lubrication, or burned contact-surfaces may 75 be the cause of making a contact switch inoperative.

It is therefore one of the objects of this invention to make and break contacts in conjunction with the operation of the locking 80 part of such devices.

Especially in so-called bi-parting doors, it is very important that the several members of such doors are securely interlocked before the operating circuit of the elevator 85 is closed; and that the several members of such doors cannot be unlocked before the operating circuit is opened or broken.

In Fig. 1, the interlocking mechanism of such bi-parting doors is illustrated in connection with a lock-switch, or contact-lock, roughly outlined. The upward and downward shifting door section 7 is connected at 8 to the flexible members 9. The other door section 10 is connected to the other ends 95 of the flexible members 9, as indicated at 11. In this manner, the two door sections are suspended so as to balance one another. Latch members 12 and 13 are pivotally mounted on one of the sections, as indicated 100 at 14, and interconnected by the connecting rod 15. The latch-ends 16 of the latch members 12 and 13 are disposed so as to engage a latch-plate 17 of the other door-section. The latch-member 12 is provided 105 with an extension-end 18 to project and extend into the lock 19, in order to keep the latch-members 12 and 13 in interlocking po-

sition in relation to the door-sections 7 and 8, by the lock-switch control, as will be described hereafter.

While Fig. 1 illustrates so-called bi-parting up and down moving doors or door sections, the device may just as well be used in conjunction with doors operated in sidewise directions. A fragmentary elevation of a sidewise moving door is indicated at 20 in Fig. 2. A latch-pawl 21 is pivotally mounted at 22 on the door 20, operative by the handle-bar 23. A slightly modified form of lock is indicated at 24, to co-operate with the other mechanism. This lock 24 as well as the lock 19, of course, is necessarily mounted on a stationary part, as, for instance, the shaft-walls, the door-frames, and any other stationary member near the doors of elevators. The pawl 21 of the slightly modified form in Fig. 2, is lifted out of engagement from the lock 24 by the handle-bar 23. The door 20 is moved back and forth by the handle-bar 23, when the pawl 21 is removed from the lock 24.

The inside contact and locking parts of the lock are illustrated in Fig. 3. A tilting member 25 is pivotally mounted at 26 within the housing or casing 27 of the lock. The tilting member 25 is provided with a bifurcated end 28, the two prongs or branches 29 and 30 of the bifurcated end 28 serving to assure a forced or positive movement of the tilting member in either direction, locking and unlocking, as well as making and breaking of contacts. On the opposite end 31 of the tilting member 25, a contact-plate 32 is provided, preferably insulated from the tilting member. A spring 33 serves to form a yielding support for the contact-plate 32, but is otherwise not responsible for the actions of the tilting member and thereby of the contacts. The contact-plate 32 is preferably provided with an elongated perforation 34, as illustrated in Fig. 6, in order to avoid or prevent a misplacing of the contact-plate in relation to the contact-blocks 35 and 36. The contact-plate 32 is shiftably mounted on the flat pin 37 of the tilting member 25. During the tilting movements of the member 25, the contact-plate 32 is shifted or moved in a sliding manner over the surfaces of the contact-blocks 35 and 36, thereby tending to clean the contacting surfaces.

In the position, indicated in dotted lines at 38, the contact-plate 32 is entirely removed from the contact-blocks 35 and 36; while in the position indicated in dash and dotted lines at 39, the contact-plate is just shifted sidewise, the pin 37 being then in the position indicated at 40, the cotter-pin 41 in the pin 37 then just hitting the contact-plate, ready to lift the contact-plate from the contact-blocks.

The end-elevation of Fig. 4 illustrates that the extension-end 18 of the latch-mem-

bers 12 and 13 of the device in Fig. 1 may enter the lock-casing through the space between the lugs 42, to come into engagement with the bifurcated end 28 of the tilting member 25.

Such an engagement with the tilting-member is more clearly illustrated in Fig. 5. The latching end 43 of the latch-pawl 21 has been used in this illustration, but it will easily be understood that the latching end of the extension-end 18 is operated with the same or similar results. The only difference is in fact that the latching pawl 21 is mainly moved in a sidewise direction with the door 20, while the extension-end 18 is mainly moved in up and down directions, aside from the short tilting movement while within the lock.

When no latch is within the lock, the tilting-member 25 is normally in the position indicated in dotted lines at 44, with the branches of the bifurcated end in the positions indicated at 45 and 46. On entering the lock, before actuating the tilting-member, the latching-end of, either, the latch-pawl 21 or the extension-end 18, takes the position indicated in dotted lines at 47. Moving the latching end of the latch-pawl 21 or of the extension-end 18 downwardly, to bring the shouldered hook 48 into engagement within the lock, as illustrated at 48, causes a tilting of the tilting-member 25 into contacting position, the hook-portion 48 pressing on the lower branch 29 of the tilting-member, thereby mechanically forcing the tilting-member to co-act with the latching mechanism.

In moving the latching-end upwardly, the latching-end is forced against the upper branch 30 of the bifurcated end of the tilting-member 25, thereby mechanically compelling a tilting of the tilting-member in the opposite direction so as to open or break the contacts. The latching-end of, either, the latch-pawl or of the extension-end 18 of the latch-members 12 and 13 cannot be removed from the lock until the contacts are broken or opened.

Having thus described my invention, I claim:

1. In an elevator-lock-switch, a housing, contacts disposed in the housing, an operating member pivotally mounted in the housing carrying a contact plate insulated from the operating member at one end and having a bifurcated termination at the opposite end of its pivot and adapted to engage the said contacts, the operating member being balanced so that the contact supporting end is in its inoperative position tilted downwardly within the housing and the bifurcated end is maintained in a tilted position with the upper member of the bifurcated end tilted backwardly spaced from the front of the housing, the housing being slotted through

a portion of the top and through a portion of the front so that a co-acting latching member may pass into the housing, the bifurcated end of the operating member being in its inoperative position disposed so that such co-acting latching member can pass the said backwardly tilted upper member of the bifurcated end while the lower member of this bifurcated end will be hit by the said latching member in passing into latching position within said housing, the said upper member of the bifurcated end being adapted to engage over such latching member when the lower member of the bifurcated end is hit by the latching member.

2. In an elevator-lock-switch, in combination with bi-parting doors within a door frame, a latch member on said bi-parting doors, a lock-housing on said frame having a slot through a portion of its top side and through a portion of its front side so that

the said latch member may pass into the housing when the said doors are so moved, a tiltably disposed operating member within the said housing having bifurcated terminations projecting in the direction of the slot in the housing so that the said latch member can pass one member of the said bifurcated terminations and adapted to hit the other end of the bifurcated terminations for tilting the operating member to operative position so as to bring the first said member of the bifurcation to a position extending over the said latch member in locked position.

In testimony that I claim the foregoing as my invention I have signed my name in the presence of two subscribing witnesses.

CHARLES A. TRAHN.
